The ornamental design for a substrate transfer blade, as shown and described.

DESCRIPTION

FIG. 1 is a top perspective view of a substrate transfer blade embodying our new design;

FIG. 2 is a bottom perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a cross-sectional view thereof taken along line 9-9 in FIG. 4; and,

FIG. 10 is an enlargement view thereof for the portion referenced in FIG. 9.

The broken lines in the drawings illustrate portions of the substrate transfer blade that form no part of the claimed design.
